UNITED STATES PATENT OFFICE.

FRANK A. BROWNE, OF WAYNE, PENNSYLVANIA, ASSIGNOR TO THE BARBER ASPHALT COMPANY, OF PHILADELPHIA, PENNSYLVANIA, A CORPORATION OF WEST VIRGINIA.

BUILDING CONSTRUCTION AND THE LIKE.

Application filed August 17, 1925. Serial No. 50,634.

My invention relates to building construction and the like, such as interior walls or partitions of dwelling houses and other buildings. I aim to provide a convenient and economical substitute for wooden or expanded metal lathing such as heretofore used for the base of plastered interior walls. In suitable forms of embodiment, my invention allows the walls to be more quickly constructed; reduces the time and labor required in plastering and in the erection of the base for the plaster; reduces the amount of plaster required; renders the wall water-proof; and makes it slower burning.

15 In carrying out my invention as herein-after described, I provide the wall with a bituminous covering mineralized or surfaced with suitably coarse, adherent mineral granules (such as particles of crushed stone, 20 slag or the like), and apply thereto the plaster that is to form the exterior of the wall. The bituminous covering may consist of superficially mineralized bituminated fabric, and may be secured directly to the main 25 wall structure or frame-work, such as the usual upright studding, braces, etc.

In the drawings, Fig. I is a fragmentary view of a wall embodying my invention, with various exterior layers partly broken 30 away to illustrate various features in the construction of the wall.

Fig. II shows a section of the wall on a larger scale than Fig. I.

The wall here shown is constructed with 35 a framing of upright wooden studding 5 and horizontal wooden braces 6 between said uprights. On the frame-work is secured the bituminated fabric covering 7, shown as consisting of felt or paper 8 (see Fig. II) saturated with bitumen and also coated there-with on one or both sides as at 9, and surfaced with small stone granules 10 embedded in the bituminous coating 9 of one face. For this covering 7 may be employed prepared roofing such as now on the market,—preferably a roofing surfaced with rather coarse mineral granules 10, that will give it an effective "tooth" to hold plaster. The material 7 may be applied in strips nailed 45 directly to the frame-work, and its joints (both longitudinal and transverse) are preferably lapped and bituminously cemented (if absolute water tightness is desired), to afford a continuous moisture-repellent and

water-proof covering. Preferably, the strips 55 of material 7 extend vertically, and are of slightly greater width than the spacing of the studding 5, (or correspond approximately in width to a multiple of such spacing), so that the strips may be lapped and 60 nailed to the studding along both margins, as shown at 11. In practice, the material 7 is also nailed as at 11 to all other members of the wall structure which it covers, such as the horizontal members 6. Any joints in 65 the strips are preferably made at the cross bracing 6 between the studding, so that they may be lapped and nailed to such bracing. In the absence of cross bracing where these joints fall, however, the lapped ends of the 70 strips may be tied or sewn together with wire, as at 12, to afford temporary stiffening.

The bituminated fabric 7 having been applied to the wall structure as described, the usual rough coat of plaster 13 (brown coat) 75 is applied directly to its granular surface 10 and allowed to set, so as to stiffen the fabric base for the application of a finishing or other subsequent plaster coat or coats. The stiffness thus afforded allows the subsequent 80 coat or coats to be applied with all necessary force without flexing the fabric base. The fabric 7 should, of course, be secured at an ample number of widely distributed points, to enable it to sustain the weight of the 85 plaster 13.

This form of construction effects a great economy in the amount of plaster used in walls, because no excess plaster is required to key into or through the base 7, as in the case of wooden or expanded metal lathing. 90 The labor of applying the flexible fabric is much less than that of applying wood laths, and the use of wood in the wall is minimized. With bituminous fabric of suitable composition, or treated with suitable substances during manufacture, the wall is 95 slower burning than if constructed with wood laths. Owing to the water-proof character of the bituminous fabric 7, moreover, a water leak in, behind, or above a wall or 100 ceiling thus constructed will not reach the plaster and stain it or cause it to fall, as is the case with lath and plaster construction.

Having thus described my invention, I 105 claim:

1. An interior wall construction comprising, in combination with the main wall

structure or studding, a covering of bitumen saturated and coated fabric, mineralized with adherent granules, secured to said wall structure; and a covering of plaster interlocked with said granules.

2. An interior wall construction comprising, in combination with the main wall structure or studding, a covering of bitumen saturated and coated paper or felt surfaced

with adherent coarse mineral granules nailed to said wall structure, and a covering of plaster applied and adhering directly to said granules.

In testimony whereof, I have hereunto signed my name at Philadelphia, Pennsylvania, this 14th day of August, 1925.

FRANK A. BROWNE.
